(57) **CLAIM**

The ornamental design for a citizens band antenna, as shown.

DESCRIPTION

FIG. 1 is a front elevational view of a citizens band antenna according to the present design;

FIG. 2 is a right side elevational view of a citizens band antenna according to the present design;

FIG. 3 is a rear elevational view of a citizens band antenna according to the present design;

FIG. 4 is a left side elevational view of a citizens band antenna according to the present design;

FIG. 5 is a top plan view of a citizens band antenna according to the present design;

FIG. 6 is a bottom plan view of a citizens band antenna according to the present design;

FIG. 7A is an enlarged, front elevational view of an upper portion of a citizens band antenna according to the present design;

FIG. 7B is an enlarged, front elevational view of a lower portion of a citizens band antenna according to the present design;

FIG. 8A is an enlarged, right side elevational view of an upper portion of a citizens band antenna according to the present design;

FIG. 8B is an enlarged, right side elevational view of a lower portion of a citizens band antenna according to the present design;

FIG. 9A is an enlarged, rear elevational view of an upper portion of a citizens band antenna according to the present design;

FIG. 9B is an enlarged, rear elevational view of a lower portion of a citizens band antenna according to the present design;

FIG. 10A is an enlarged, left side elevational view of an upper portion of a citizens band antenna according to the present design; and,

FIG. 10B is an enlarged, left side elevational view of a lower portion of a citizens band antenna according to the present design.
